US00D883836S

(12) **United States Design Patent** (10) **Patent No.:** **US D883,836 S**
(45) **Date of Patent:** **** May 12, 2020**

(54) **SMART BRACELET BAND**

(71) Applicant: **SHENZHEN LOOKCARE INDUSTRY CO., LTD.**, Shenzhen, Guangdong (CN)

(72) Inventor: **Yongjian Zheng**, Guangdong (CN)

(73) Assignee: **SHENZHEN LOOKCARE INDUSTRY CO., LTD.** (CN)

(**) Term: **15 Years**

(21) Appl. No.: **29/672,302**

(22) Filed: **Dec. 4, 2018**

(51) LOC (12) Cl. **11-01**

(52) U.S. Cl.

USPC **D11/3; D14/344**

(58) **Field of Classification Search**

USPC D11/1-6, 9-20, 40-45, 48, 78.1, 79, 80, D11/81, 86, 87, 93, 94, 26, 38, 39, 231, D11/234, 235; D10/32, 37; 116/321, 116/322; D19/1-8; D24/194; D30/160; D14/344

CLAIM

The ornamental design for a smart bracelet band, as shown and described.

DESCRIPTION

FIG. 1 is a front view of the smart bracelet band showing our new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a top perspective view thereof; and,

FIG. 8 is a bottom perspective view thereof.

1 Claim, 6 Drawing Sheets
